(57) **CLAIM**

The ornamental design for a wake surf fin, as shown and described.

DESCRIPTION

FIG. 1 is a bottom perspective view of the wake surf fin; FIG. 2 is a top perspective view of the wake surf fin; FIG. 3 is a right, side elevation view of the wake surf fin, the left side being a mirror image thereof;

FIG. 4 is a top plan view of the wake surf fin;

FIG. 5 is a bottom plan view of the wake surf fin; FIG. 6 is a front elevation view of the wake surf fin; and, FIG. 7 is a rear elevation view of the wake surf fin.

The broken lines shown in the drawings are for the purpose of illustrating portions of the article that form no part of the claimed design.
